UNITED STATES PATENT OFFICE.

CHARLES F. KETTERING, OF DAYTON, OHIO, ASSIGNOR TO THE DAYTON ENGINEERING LABORATORIES COMPANY, A CORPORATION OF OHIO.

ENGINE-CONTROL SYSTEM.

Application filed May 26, 1919. Serial No. 299,762.

To all whom it may concern:

Be it known that I, CHARLES F. KETTERING, a citizen of the United States of America, residing at Dayton, county of Montgomery, State of Ohio, have invented certain new and useful Improvements in Engine-Control Systems, of which the following is a full, clear, and exact description.

This invention relates to systems of control for internal-combustion engines and has among its objects the prevention of racing of the engine when the starting device is connected with it. This racing of the engine would not only be injurious to the engine itself but might be injurious to the starting device in case the starting device were not immediately disconnected from the engine as soon as the starting operation had been effected.

Other and further objects of the present invention will be apparent from the following description, reference being had to the accompanying drawings, wherein a preferred embodiment of the present invention is clearly shown.

In the drawings:

Fig. 1 is a side elevation of an internal-combustion engine provided with a starting device and with the system of control for the starting device and engine including the present invention;

Fig. 2 is a plan view of the elements shown in Fig. 1;

Fig. 3 is a sectional view of the starting device taken on the line 3—3 of Fig. 2; and

Fig. 4 is an elevational view similar to Fig. 1 showing the positions taken by certain of the controlling elements while the starting device is mechanically connected with the engine.

In the drawings, 20 indicates an internal-combustion engine of the automobile type which is located in front of and below the automobile floor board, a fragmentary section of which is shown at 21 in Fig. 1. 22 refers to the usual type of steering wheel of the automobile which is connected with a steering column 23 for actuating the steering gear, not shown.

A throttle lever 24 located above the steering wheel 22 is connected with a tube 25 extending down through the steering column 23 and carrying at its lower end a lever arm 26. The engine 20 is provided with carburetor 30 having a butterfly throttle valve

31 mounted on shaft 32. Shaft 32 carries lever 33 which is connected by link 34 with a lever 35 secured upon a shaft 36 which is rotatably journaled upon the engine frame. Shaft 36 carries lever 37 the outer end of which is connected with a link 38 provided with ears 39 and 40. A link 41 connected at one end with lever 26 projects through aligned apertures in ears 39 and 40 and carries fixed collars 42 and 43. A spring 44 is interposed between collar 42 and ear 40. It will be seen that by means of this connection just described movement of the throttle lever 24 in a counter clockwise direction as viewed in Fig. 2 will effect the opening of the throttle valve 31 and the clockwise movement of the lever 24 will effect the closing of said throttle valve.

The throttle valve 31 may be controlled independently of the manual throttle lever 24 by means of an accelerator pedal 50 which is pivotally mounted upon the floor board 21 and provided with a lever arm 51 which is connected by link 52 with a lever 53 fixed upon the shaft 36. When the accelerator pedal 50 is depressed clockwise motion will be imparted to the shaft 36 causing lever 35, link 34 and lever 33 to be moved upwardly to open the throttle valve 31. When this occurs link 38 may move independently of link 41 compressing the spring 44 and permitting the throttle lever 24 to remain in the position in which it has been placed manually. As soon as the accelerator pedal 50 is released the spring 44 will expand forcing the link 38 downwardly until the ear 40 abuts against the collar 43. In this manner the spring 44 restores valve 31 to a position corresponding to the setting of throttle lever 24.

The engine is provided with a starting device 60 which is secured upon the frame of the engine 20 in any suitable manner. The starter 60 includes an electric motor having field windings 61 and an armature 62, a commutator 63 and a spur gear 64 mounted upon an armature shaft 65. Gear 64 meshes with a speed reduction gear 66 which is mounted upon a counter shaft 67. A pinion 68 having a sliding driving connection with the shaft 67 is arranged to be brought into engagement with a flywheel gear 69 when it is desired to start the engine. The movement of pinion 68 is controlled by a starting pedal 70 slidably mounted in a bushing 71 carried by the floor board 21. The downward move-

- ment of pedal 70 is resisted by a spring 72 interposed between the head of pedal 70 and the bushing 71. Pedal 70 is connected by link 73 with lever 74 which is pivoted at 75.
- 5 One end of lever 74 is operably connected with a sliding collar 76 slidably mounted on the shaft 67. A spring 77 is interposed between collar 76 and the pinion 68. It is apparent that by depressing pedal 70 motion 10 will be imparted to pinion 68 from the spring 77 in such a manner as to cause pinion 68 to be brought into engagement with the flywheel gear 69.
- The connection between link 73 and lever 15 74 is effected by means of a pin 80 which projects through a slot 81 provided in a brush lifting lever 82. Lever 82 is pivotally mounted at 83 upon the frame of the starting device, and one end of this lever is 20 arranged to contact with a plunger 84 for the purpose of maintaining the motor brushes out of engagement with the motor commutator when the starting device is inoperative. The slot 81 is so arranged with 25 reference to the movements of lever 74 that after the pedal 70 has been depressed to a certain extent which is sufficient to bring the pinion 68 into substantial engagement with the flywheel gear 69, a movement of lever 82 30 will take place causing the motor brushes to be brought into engagement with the motor commutator to effect the connection of the motor and the battery or other source of starting current.
- 35 Referring to Fig. 3, the lever 82 engages a pin 100 mounted to slide within the motor frame and to engage brush arm 101 carrying brush 106. When lever 82 is in the position shown in Fig. 1 and Fig. 3, brush 106 40 is maintained out of contact with commutator 63. Brush arm 101, when in the position shown in Fig. 3, in turn maintains brush 105 out of engagement with commutator 63, as said arm 101 is provided with 45 a lug 103 engaging lever 104 which in turn engages lug 105 carried by the brush arm 102 on which the brush 107 is mounted. Brushes 108 and 109 are mounted upon arms 110 and 111, respectively. Springs 112 50 serve to hold the brushes 108 and 109 in engagement with the commutator 63 at all times. When pedal 70 is depressed as shown in Fig. 4 lever 82 will be moved upwardly to release pin 84 and to permit brushes 106 and 107 to be moved by springs 113 into engagement with the commutator 63.

60 The particular detail description of the various operations of this starting device is disclosed in the copending application of William A. Chryst Serial No. 296,393, filed May 12, 1919, and further detail description of this application is considered unnecessary.

65 The lever 74 is connected with a link 90 which projects through an aperture 91.

formed in the outer end of lever 92 which is mounted in fixed relation with the shaft 36. A collar 93 is mounted upon the link 90 in such a relation to the lever 92 that when the starting pedal 70 is inoperative or 70 in the released position as shown in Fig. 1, the valve 31 may be moved to full open position either by means of the throttle lever 24 or the accelerator pedal 50. If before starting the engine the throttle 31 is moved 75 to full open position as shown in Fig. 1 by the movement of lever 24 to the upper position as shown in Figs. 1 and 2, the engine would race upon becoming self-operative with the result of injurious effects upon the 80 engine and the starting device. However, in the present invention such a condition of affairs cannot take place for when the starting pedal 70 is depressed the link 90 will be moved to the left as viewed in Fig. 1, causing motion to be transmitted to the lever 92 through the collar 93 such as to move the valve 31 toward closed position. When the starting pedal 70 is fully depressed to effect the starting operation by moving gear 68 90 into engagement with fly-wheel gear 69 and by effecting the connection of the starting motor in the manner described, the device controlling the throttle will have been moved at the same time into the position shown in 95 Fig. 4 of the drawings. With the controlled devices in these positions, the throttle valve 31 will occupy a partially closed position as shown in Fig. 4.

100 It is apparent from the foregoing description that a system control has been provided whereby it is impossible to race the engine as soon as the starting pedal is depressed. The depressing of the pedal 70 will cause the hand lever 24 and the foot lever, or accelerator pedal 50 to move from the position shown in Fig. 1 to the position shown in Fig. 4. Any movement of these members 24 and 50 to the position shown in Fig. 1 105 will be resisted as long as the foot is held upon the pedal 70. In this manner racing of the engine during the starting operation is prevented, and consequently excessive rotation of the motor shaft 65 by the engine, before the motor shaft can be disconnected, 110 is prevented. Normally the spring 72 effects the return movement of the pedal 70 and consequently the disengagement of the gears 68 and 69. But should this spring 72 115 become ineffective for any reason, then the disengagement of the gears 68 and 69 may be effected by moving the pedal 50 from the position shown in Fig. 4 to the position shown in Fig. 1.

120 While the form of mechanism herein 125 shown and described constitutes a preferred form of embodiment of the invention, it is to be understood that other forms might be adopted, all coming within the scope of the claims which follow.

What I claim is as follows:

1. In an engine control system, the combination with an internal-combustion engine having a throttle valve; manual means for controlling the throttle valve; a starting device for the engine; and means for controlling said starting device and said manual means to limit to a partly open position the opening of said throttle by said manual means whereby to prevent racing when the engine becomes self-operative.
2. In an engine control system, the combination with an internal-combustion engine having a throttle valve; manual means for controlling the throttle valve; a starting device for the engine; and means for controlling said starting device and said manual means to limit to a partly open position the opening of said throttle by said manual means whereby to prevent racing when the engine becomes self-operative, said starting device controlling means permitting a limited control of said throttle by said manual means.
3. In an engine control system, the combination with an internal-combustion engine having a throttle valve; manual means for controlling the throttle valve; a starting device for the engine including a power device and gearing to connect the same with the engine; and means for controlling the power device for moving certain of said gearing into and out of mechanical connection with the engine and for limiting to a partly open position the opening of the throttle by said manual means.
4. In an engine control system, the combination with an internal-combustion engine having a throttle valve and a gear; manual means for controlling the throttle valve; a starting device including an electric motor and a motor pinion shifting into connection with said engine gear; and means for rendering the motor operative, for moving said pinion into and out of engagement with said engine gear and for limiting to a partly open position the opening of said throttle by said manual means.
5. In an engine control system, the combination with an internal-combustion engine; of means for controlling the speed of operation of the engine; a starting motor normally disconnected from the engine; and means for connecting the starting motor with the engine and for controlling said speed controlling means whereby the engine speed is limited to a value less than maximum.
6. In an engine control system, the combination with an internal-combustion engine having a gear; of a starting motor having
- a gear connected therewith, means for controlling the speed of operation of the engine; and means for connecting said gears and for controlling said speed controlling means whereby the engine speed is limited to a value less than maximum.
7. In an engine starting system, the combination with an internal-combustion engine having a throttle; of a starting device; means for controlling the throttle including a hand lever and a foot pedal, the movement of the foot pedal permitting the setting of the hand lever to remain undisturbed; and means for rendering the starting device operative and for limiting the movement of the throttle by either the hand lever or the foot pedal to a predetermined partly closed position.
8. In an engine starting system, the combination with an internal-combustion engine having a throttle; of a starting device; normally disconnected gearing between the starting device and engine; means for controlling the throttle including a hand lever and a foot pedal, the movement of the foot pedal permitting the setting of the hand lever to remain undisturbed; and means for connecting said gearing and for limiting the movement of the throttle by either the hand lever or the foot pedal to a predetermined partly closed position.
9. In an engine starting system, the combination with an internal combustion engine having a throttle; of a starting device; normally disconnected gearing between the starting device and engine; means for controlling the throttle including a hand lever and a foot pedal, the movement of the foot pedal permitting the setting of the hand lever to remain undisturbed; and means for rendering the starting device operative, for connecting said gearing and for limiting the movement of the throttle by either the hand lever or the foot pedal to a predetermined partly closed position.
10. In an engine control system, the combination with an internal combustion engine; of an engine starting device; means for controlling the speed of the engine; and means for rendering the starting device operative to crank the engine and for controlling said speed controlling means whereby the engine speed is limited to a value less than maximum.

In testimony whereof I affix my signature.

CHARLES F. KETTERING.
